(57) **CLAIM**

The ornamental design for a hook part, as shown and described.

DESCRIPTION

FIG. 1 is a perspective view of a hook part embodying this invention, with additional hook parts and a mounting bar shown in phantom;

FIG. 2 is a top view of the hook part shown in FIG. 1, with the additional hook parts and mounting bar shown in phantom;

FIG. 3 is a front view of the hook part shown in FIG. 1, with the additional hook parts and mounting bar shown in phantom;

FIG. 4 is a right side elevation view of the hook part shown in FIG. 1, with the mounting bar shown in phantom;

FIG. 5 is a rear view of the hook part shown in FIG. 1, with the additional hook parts and mounting bar shown in phantom;

FIG. 6 is a left side elevation view of the hook part shown in FIG. 1, with the mounting bar shown in phantom; and, FIG. 7 is a bottom view of the hook part shown in FIG. 1, with the additional hook parts and mounting bar shown in phantom.

The broken line showing of remaining hooks and rack is for illustrative purposes only and forms no part of the claimed design.
